UNITED STATES PATENT OFFICE.

CARL W. SWENSON, OF PROVIDENCE, RHODE ISLAND, ASSIGNOR TO ARNOLD C. MESSLER, OF PAWTUCKET, RHODE ISLAND.

HEADING-MACHINE.

1,243,003.

Specification of Letters Patent. Patented Oct. 16, 1917.

Application filed January 12, 1917. Serial No. 142,106.

To all whom it may concern:

Be it known that I, CARL W. SWENSON, a citizen of the United States, residing at Providence, in the county of Providence and 5 State of Rhode Island, have invented certain new and useful Improvements in Heading-Machines, of which the following is a specification.

My invention relates to a machine adapted 10 to form the head portion of the movable member of a ball and socket fastener.

The essential objects of my invention are 15 to insure speed of production, and accuracy of shape in the product; to provide adequate feeding and discharging means; to prevent cramping of the blank during its passage through the forming tools; and to prevent clogging of the blanks as they are fed to the forming tools.

20 To the above ends essentially my invention consists in such parts and combinations of parts as fall within the scope of the appended claims.

25 In the accompanying drawings which form a part of this specification

Figures 1 and 2 are side and plan elevations respectively of a machine embodying my invention, parts being broken away to more clearly show operative parts,

30 Fig. 3, a section on line 3—3 of Fig. 2,

Fig. 4, a fragmentary elevation of the lower front portion of the hopper wall,

Fig. 5, a transverse section, partially diagrammatic, of a portion of the hopper wall 35 and of the adjacent forming mechanism on line 5—5 of Fig. 4, showing in broken lines various positions assumed by an advancing blank,

40 Figs. 6 and 7, sections of the forming channel on lines 6—6 and 7—7 respectively of Fig. 2,

Fig. 8, a fragmentary elevation of the lower margin of the rotary conveyer, showing the adjacent portion of the hopper wall 45 in section,

Fig. 9, a section on line 9—9 of Fig. 8, and

Figs. 10 and 11, elevations of the original and completed blanks respectively.

50 Like reference characters indicate like parts through the views.

My machine has a frame of any form best adapted to support the operative parts. In the form thereof herein shown, it comprises 55 an attaching plate 14, front and rear sup-

ports 15 and 16 respectively, and a table or base plate 17 upon the supports. Journalized in the forward portions of the plates 14 and 17 is a driving shaft 19, and in the rear thereof a driven shaft 20. The former is 60 driven by a pulley 21 through a belt 22 from any convenient source of power, and a gear 23 on the shaft 19 meshes with a gear 24 on the shaft 20. The forward portion 25 of the plate or table 17 is substantially circular, and has upon its upper face a marginal annular shoulder 27 to whose upper surface is fixed by screws 28 or otherwise an ar- 65 cuate plate or die 29 projecting inwardly from the shoulder and provided upon its inner margin with an annular bevel portion 30. Its periphery is provided with a curved groove 31 forming two annular resultant projecting upper and lower portions or shoulders 33 and 34 respectively, the lat- 70 ter projecting more than the former. The shoulder 34 is provided with minute teeth 35 or has its surface otherwise roughened, as shown in Fig. 5. Coöperating with the plate 29 is a rotary member, represented in 75 a general way by the reference numeral 37 comprising a disk 38 fixed to shaft 19 ex- 80 tends below the member 29 and spaced therefrom, and upon whose central portion is a spacing shoulder 39. The rotary mem- 85 ber is completed by a circular plate or die 40 of less diameter than the disk 38, and having its lower face in the horizontal plane of the lower face of the plate 29. Its upper 90 face has a marginal bevel 41. The portions 38 and 40 of the member 37 may, if desired, be integral with each other, it being necessary in either case that the space or marginal re- 95 cess 43 between the members be present. The plate 40 may be fixed to the disk 38 or 100 to the shaft 19 in any preferred manner. The periphery of the die 40 has an annular groove 47 forming resultant upper and lower shoulders 48 and 49, the latter extend- 105 ing the greater distance. The shoulder 49 has minute teeth 50 or a surface otherwise roughened throughout its periphery. The shoulders 33 and 34 are respectively oppo- 110 site and in the horizontal planes of the shoulders 48 and 49. Thus is formed a guideway or space between the dies 29 and 40 represented in a general way by the reference numeral 51 with a restricted passage 52 formed by the lower pair of shoulders, as shown in Fig. 6, and an enlarged trans-

versely curved passage 53 above the latter passage. The die 40 is disposed slightly eccentric to the die 29 so that the guideway is of gradually diminishing width from the entrance 55 thereof to an intermediate point. This difference in width is illustrated in Figs. 6 and 7.

The portion 57 of the table 17 in the rear of the portion 25 is also circular and of greater diameter and is provided with vertical lugs 58 having holes 59 to admit screws 60 to engage and rigidly maintain a circular wall 61 elevated above the table, which wall constitutes the side of a hopper. A disk 62 fast to the shaft 20 rotates in sliding contact with the bottom edge of this wall and constitutes the floor of the hopper. This disk has its periphery in contact with the periphery of the part 38 of the die 37, and its upper face is in the plane of the upper face of said part. The wall 61 abuts against the plate 29 at the end of the latter where the entrance 55 occurs, and is provided in its lower edge with a long arcuate shallow slot 64 from which extends a deep slot 65. At one side of the slot 65 the wall 61 has its surface inclined, as at 66, as shown in Fig. 5, forming a pointed projection 67. The wall 61 at the opposite side of the slot is cut away to form a tapering surface 68 or reduced wall portion.

Removably fixed to the shaft 20 is a hub 70 having radial arms 71 integral with a cylindrical wall or open drum 72, of slightly less diameter than the wall 61, and which constitutes a rotary spacing or selecting member. It has gear teeth 73 upon its periphery. The lower edge of this member is adjacent or in contact with the face of the disk 62, and is provided with a series of spaced marginal reversed T shaped openings 74 each comprising a shallow portion 75, and a deep central portion 76. The side walls of the openings 74 are transversely inclined, as shown in Fig. 9, and the portions of the wall adjacent the opposite sides of the openings are of different degrees of thickness, forming the projection 78 and the guide surface 79. The described parts are for feeding the blanks to the forming dies. A gear 79 fast on the shaft 19 meshing with the teeth 73 drives the drum 72 preferably at a less speed than the rotation of the disk 62.

The means for discharging the formed blanks comprises an arcuate attaching strip 80 fixed by screws 81 to the top of the die 29 and carrying an upright curved wall or flange 82 integral with a downwardly inclined tube 84. Fixed to the shoulder 27 by screws 85 is a guide plate 86 extending into the cavity 43 some distance at a point within or adjacent the mouth of the tube 84.

The operation of the machine is as follows: The blanks are introduced in quan-

tities into the hopper. Each blank, as shown in Fig. 10, comprises the flange or base 87 and a hollow post 88. By the centrifugal force of the disk 62, the blanks are driven radially until their bases respectively enter the slots 64, 65, and advance into contact with the point 67 and are induced along the inclined face 66 into the guideway 51, as shown in Fig. 5. The flange of each blank slides into the recess 43 of the die 37 and beneath the die 29. The rotating die, engaging the post of the blank, impels the blank along the guideway as well as imparting rotary movement thereto. These movements are facilitated by the marginal teeth 35 and 50. As the blank advances from the broad to the narrow portions of the guideway, the dies continuously and gradually compress and shape the post of the blank into the rounded or spherical head 89 shown in Fig. 11. The shoulders 34, 49 and grooves 31, 47, assist to impart this final form. During the travel of the blank, its flange finally contacts with the plate or projection 86 whereby the blank is disengaged from the dies or runway and falls through the tube 84. The blanks move through the guideway successively and in contact with each other insuring speed, quantity of production, and accuracy of form.

The long slot 64 in the wall 61 affords means for slidably engaging and guiding a row of blanks through the opening 65, but in order to prevent choking the former slot by overlapping flanges due to an excessive massing of blanks, the rotary selective member is advantageously employed. The spaced openings 74 therein permit passage therethrough of only a limited number of blanks. These are selectively induced through the openings by the disk 62, rotating at greater speed than the member 72, and are assisted by the shape of the latter adjacent the opening.

Other modes of applying the principles of my invention may be employed instead of the one explained, change being made as regards the mechanism herein disclosed, provided the means stated by any of the following claims or the equivalent of such stated means be employed.

I claim:—

1. In a machine of the character described, the combination of a concave die, a circular die adjacent thereto having its periphery arranged relatively to the first die to form a curved guideway between the dies, a rotary feed disk in contact with the periphery of the circular die, and means for rotating the feed disk.

2. In a machine of the character described, the combination of a fixed arcuate die, a circular rotary die adjacent the first die, and coöperating therewith, said rotary die being provided with an annular recess in its face,

and a rotary feed disk in contact with the rotary die and detached therefrom and having its face in the plane of the recess.

3. In a machine of the character described, 5 the combination of a fixed arcuate die, a circular rotary die adjacent the first die coöperating therewith comprising a disk and a superposed plate of less diameter than the disk spaced from the disk, a rotary feed disk 10 engaging the first disk, means for rotating said disk, a stationary wall in slidable contact with the upper marginal face of the feed disk provided with a marginal slot adjacent the rotary die, and an inclined projection 15 on the wall at one side of said slot.
4. In a machine of the character described, 20 the combination of a fixed die, a rotary circular die adjacent thereto provided with an annular recess, a rotary feed disk engaging the periphery of the rotary die with the top 25 face of the disk flush with the recess, a stationary wall in contact with the margin of the top face of the disk provided with an elongated marginal slot above the disk adjacent the die and with an enlargement of 30 said slot near one end thereof, and a projection on the wall at one side of the enlarged portion of the slot.
5. In a machine of the character described, 35 the combination of a frame, a vertical driving shaft mounted in the frame, a circular die fast to the shaft, an arcuate die fixed to the frame adjacent the first die and coöperating therewith, a vertical driven shaft 40 mounted in the frame, a feed disk fast to the driven shaft engaging the periphery of the circular die, a cylindrical wall fixed to the frame in contact with the margin of the top face of the disk provided with a slot 45 adjacent the circular die, gears on the shafts meshing with each other, and means for actuating the driving shaft.

6. In a machine of the character described, 50 the combination of a stationary tubular wall provided with a marginal slot, a rotary feed disk engaging and closing the bottom of the wall and bounding the slot, a rotary forming die exterior of the wall adjacent the slot engaging the disk, and means actuating the disk for rotating the die.

7. In a machine of the character described,

the combination with the frame, of a rotary shaft in the frame, a tubular wall fast to the frame provided with a marginal slot, a feed disk fast to the shaft engaging and closing 55 the bottom of the wall and bounding the slot, a rotary drum loose upon the shaft within the wall slidably engaging the disk and provided with marginal slots bounded by the disk, and means for rotating the disk 60 and drum at different relative speeds.

8. In a machine of the character described, 65 the combination with the frame, of a driving shaft in the frame, a tubular wall upon the frame provided with a marginal delivery slot, a driven shaft in the frame, a feed disk fast on the driven shaft engaging the bottom of the wall, a selecting drum loose on the driven shaft within the wall, a gear on the driven shaft, a gear connection between 70 said gear and the driving shaft, and means upon the driving shaft for rotating the drum.

9. In a machine of the character described, 75 the combination with the frame, of a driving shaft in the frame, a tubular wall upon the frame provided with a marginal delivery slot, a driven shaft in the frame, a feed disk fast to the driven shaft engaging the bottom of the wall, a selecting drum 80 loose on the driven shaft within the wall, gear teeth upon the drum, gears connecting the shafts, and a gear on the driving shaft engaging the gear teeth.

10. In a machine of the character described, 85 the combination of a stationary tubular retaining wall provided with a marginal delivery slot, a rotary disk closing the bottom of the wall and bounding the slot, a shaft to which the disk is fast, a rotary 90 selecting drum loose on the shaft within the wall and concentric therewith, said drum being provided adjacent the disk with spaced slots, projections upon the drum at one side of the slots, and means actuating the drum 95 for rotating the shaft.

In testimony whereof I have affixed my signature in presence of two witnesses.

CARL W. SWENSON.
